UNITED STATES PATENT OFFICE.

LOUIS FORT, OF JERSEY CITY, NEW JERSEY.

ADJUSTABLE INSULATOR-SUPPORT.

1,097,414.

Specification of Letters Patent. Patented May 19, 1914.

Application filed February 6, 1913. Serial No. 746,537.

To all whom it may concern:

Be it known that I, Louis Fort, a citizen of the United States, and a resident of Jersey City, in the county of Hudson and State of New Jersey, have invented certain new and useful Improvements in Adjustable Insulator-Supports, of which the following is a full, clear, and exact description, whereby any one skilled in the art may make and use the same.

The invention relates to insulator supports and more particularly to an insulator support having features of adjustment with reference to a supporting member as herein-after defined.

The object of the invention is to provide a simple inexpensive bracket or support for insulators which may be adjusted to cross-arms of various cross-sections.

A still further object is to provide in the adjusting members for the support locking devices which will prevent accidental loosening and disarrangement of the bracket through vibration strains, etc.

Referring to the drawings Figure 1 is a perspective view of the bracket illustrating its method of attachment to a cross-arm of rectangular cross section. Fig. 2 is a sectional view in plan on a horizontal plane denoted by the line 2-2 of Fig. 1. Fig. 3 is a perspective view of one of the leveling blocks. Fig. 4 is a detail view in modified form in which the locking surfaces are arranged at right angles to each other rather than at oblique angles.

In applying insulator supports or brackets to cross arms and the like, it has been common practice to provide a bracket with means for permanently and definitely fastening said bracket to the cross arm. It has also been a practice to use a metal bracket having a loop extending about the cross arm and with fastening devices such as nuts and screw threads at two ends of the loop for binding the bracket in place against the cross arm. The present invention contemplates more than this and provides for adjustment which might be termed "universal" in as much as the clamping bar which passes about the cross arm or the like may be so adjusted with reference to the fixed arms of the bracket that the device might be secured to cross arms of different cross sections and when once set in place and locked will, from the nature of the fasten-

ings and arrangement of parts be firmly and positively clamped.

The device hereinafter defined has particular advantages in use on cross arms where it is desired to take off laterals from a main line. The device may be readily adjusted to the cross arm and secured thereto and is so constructed that it will withstand heavy strains.

Referring to the drawings there is illustrated at 1 in dotted outlines a section of the cross arm which as herein illustrated is of rectangular form. The insulator support or bracket is composed of suitable material and may be formed in any desired manner as by casting or forging or, of course, may be assembled from sections of metal suitably secured together.

The bracket in the main comprises a saddle member 2 composed of a flat web-like member 3 arranged in a vertical position and a similar flat web-like member 4 arranged substantially at right angles thereto and as shown, in a horizontal position over the flat cross arm 1. The web 3 is continued in suitable curved form as at 5 and terminates in a threaded end 6 upon which a suitable insulator may be screwed. The web 3 also extends downwardly and in an upwardly sweeping curve 7 terminates in a threaded member 8 similar to the member 6 to which an insulator 9 of suitable character may be secured.

A stiffening web 10 extends medially of the web or flange 3 from the threaded insulator support 6 to the threaded insulator support 8 and at one point adjacent to what would be the bottom line of the cross arm is enlarged into a boss 11 having an angularly formed face 12 and an elongated perforation 13. This perforation passes through the web 3 and permits the adjustment of one end of the clamping bar 14 which passes under the cross arm 1 and extends up the rear thereof through an elongated perforation 15 formed through the boss 16 which is arranged at the end of the stiffener web 17 and flange or web 4. This boss 16 has an angularly disposed face 18 which, as illustrated in the drawings, is obliquely disposed and opposed to the angularly formed face of the boss 11. Overlying the perforated bosses 11 and 16 are binding blocks 19, 20 shown in detail in Fig. 3. Each of these blocks has side lips 21, 22, which overlie the 110

edges of the bosses 11 and 16 and are provided with a central perforation 23, through which the threaded ends of the clamping bar 14 extends, which bar, through nuts 24, 5 25, may be clamped firmly against the cross arm, thus holding the bracket in a defined position.

The blocks 19, 20 are of tapered form so that whatever the position of the clamping bar in the horizontal or vertical position, 10 the nuts will bind firmly and squarely against the upper surface of the tapered blocks. The taper of the block of course corresponds to the incline of the perforated boss and when the nuts are once 15 firmly screwed down with the bracket adjusted upon the cross arm, the tendency is to bind tighter and tighter under any given strain. In Fig. 4 the bosses 30 and 31 20 are illustrated as having faces substantially at right angles to each other.

The perforations 32, 33 are of elongated form so that an adjustment of the clamping bar 34 may be effected in two directions, 25 thus permitting adjustment to cross arms of various cross sections. As in the device heretofore described, a universal adjustment is thus provided, but in lieu of the tapered or wedge-shaped members underlying the 30 nuts 36, 37, rectangular blocks or washers 38, 39 are employed. This form of the device, while of somewhat simpler form, lacks the inclined form of binding surface of Figs. 1 to 3 and will not have the inherent clamping action toward the angle of 35 the bracket when setting down the binding nuts. Of course, the clamping bar is capable of adjustment in two directions and if snugly fitted and tightly clamped, provides a substantial holding device with the 40 features of adjustability.

In the form described in Figs. 1 to 3, the tightening of the nuts tends to draw the bracket firmly against the cross arm as the 45 clamping bar is tightened in both directions. It will be noted that the webs of the bracket are of substantial width so that a firm hold or seat is given for the bracket with reference to the cross arm, thus unusual 50 strains may be placed upon the insulators without liability of the bracket turning or becoming displaced and without liability of its cutting into the material of the cross arm.

55 Obviously, the exact form of bracket and arrangement of insulators might be varied to a great extent without departing from

the spirit or intent of the invention and in lieu of having two arms with threads for supporting insulators, a single arm either 60 dependent and similar to the arm 7 or extending upwardly as the arm 5 might be used. In fact, the arrangement of insulator supporting arms is immaterial, the essence of the invention residing in the arrangement of the bracket having a saddle with a clamping bar universally adjustable with reference to the two parts of the saddle, whereby it may be adjustable with reference to and secured to cross arms of 65 various cross sections.

What I claim as my invention and desire to secure by Letters Patent is:

1. An adjustable insulator support having means for supporting an insulator embodying a saddle part comprising two members angularly disposed to embrace two sides of a cross arm, tapered bosses arranged on each of said members, said bosses having their tapers extending toward each other, 75 a clamping bar arranged to embrace two sides of the cross arm and having its ends projecting beyond the tapered bosses of the saddle member and devices for drawing the clamping bar to cause said bar and saddle member to bind against the cross arm. 85

2. An adjustable insulating support having means for supporting an insulator embodying a saddle comprising two members angularly disposed to embrace two sides 90 of a cross arm, bosses having elongated perforations arranged on each of said members, said bosses having angularly disposed faces, perforated binding blocks fitting said tapered faces, a clamping bar extending 95 through the perforated bosses and binding blocks and devices for drawing said clamping bar through said blocks.

3. In a device of the character described, a saddle-like member having angularly arranged extensions embracing two sides of a cross arm, tapered bosses having elongated perforations arranged in each of said extensions, perforated blocks of wedge-shape overlying said perforated bosses and 105 provided with dependent flanges embracing the sides thereof, a clamping bar having its ends protruding through said wedge-shaped blocks and nuts engaging the ends of said clamping bar.

LOUIS FORT.
